POWER REGULATOR

Nathaniel Rochester, Milton, Mass., assignor to
 Sylvania Electric Products Inc., Salem, Mass.,
 a corporation of Massachusetts

Application June 27, 1946, Serial No. 679,841

4 Claims. (Cl. 315—97)

1

This invention relates to means for regulating the temperature of the cathode heater in an electronic device and particularly to such means acting automatically to regulate such temperature within small limits.

An object of the invention is to provide means for maintaining stable cathode emission conditions within an electronic device.

A further object of the invention is to provide means to regulate the emission of the cathode of an electronic tube by utilizing the thermal emission characteristics of a cathode in a control tube which may otherwise be non-functional with respect to the circuit containing the regulated tube.

A further object of the invention is to provide means for removing the source of power from the cathode within a cathode emission regulated tube when the regulating means fails.

Other objects and features of the invention will more fully appear from the following description and will be particularly pointed out in the claims.

The present invention involves the use of an auxiliary control tube to regulate the cathode emission of one or more other electronic tubes which are employed in any apparatus requiring such tubes for its operation. The tube or tubes to be regulated desirably are of the indirectly heated cathode type having a heater element, thermally but not electrically, connected to the cathode. However, other types of cathodes having a relatively slow thermal response may be regulated.

The control tube is provided with a cathode which has a relatively rapid thermal response and may be a simple diode tube. The cathode of the control tube is connected to and receives power from the source of current which supplies power to the cathode or heater of the tube to be regulated. The plate circuit of the control tube is supplied with power and has connected therein a normally closed relay switch for operation by power conducted by and through the control tube. The switch contacts of the relay are connected to open and close the power circuit to the two cathodes.

When the power is turned on the cathodes heat up and since the control tube cathode has a more rapid thermal response it becomes emissive and therefore conductive before the other cathode. The relay is thus actuated to open the main power supply circuit. The control tube cathode then starts to cool to non-emissive temperature at which time the relay switch closes to start another heating cycle.

Repeated heating cycles maintain the cathode

2

of the regulated tube at a desired temperature determined by the thermal emission characteristics of the control tube cathode.

To provide a better understanding of the invention preferred embodiments thereof will now be described. Such embodiments are illustrated in the drawings in which Figure 1 is a diagrammatic view of a basic form of the invention, and Figure 2 is a diagrammatic view of a different form of the invention.

It is of great practical advantage in many applications of the electronic tube or other electronic device, to maintain the electronic emission of the cathodes of such devices constantly within close limits. The present invention provides a highly effective means for accomplishing such a result.

The thermionic tube 1 is the electronic device to be regulated. This tube may be of any type and is shown herein as a diode having a plate 2, a cathode 3 and a heater element 4. The tube 1 may be incorporated in any desired circuit and since its function therein constitutes no part of the invention no circuit therefore is shown.

Power to energize the heater 4 is derived from any suitable source such as a transformer 5 which in turn is connected to a primary power source. The heater 4 is connected to the transformer 5 by the leads 6. A cathode 7 within the control tube 8 is also connected to the leads 6. If desirable or necessary a compensating resistor 9 may be inserted in one of the leads to the cathode 7.

The control tube 8 may be of any suitable type but should have a cathode having a thermal response substantially shorter than the cathode of the tube to be controlled. As shown herein the tube 8 is a diode having its plate 10 connected to a suitable source of direct current or other source of power and has connected in its plate lead 11 the magnet 13 of relay switch 12. The switch contacts 14 of the relay are connected in one of the leads 6 where they function to turn on and off the supply of power to the cathodes 3 and 7. The relay is adjusted to normally close the power circuit to the tube cathodes.

When the power is turned on to the cathodes and plate 10 the heater 4 and the cathode 7 start to heat up. Because of the relatively rapid response of the cathode 7 it becomes electron-emissive soon after the power is turned on. As soon as the control tube becomes conducting the relay 12 acts to cut off the power to the cathodes which start to cool. The cathode 7 again being the more responsive element quickly cools to the non-conducting temperature at which time the relay

turns on the power to the cathodes and the heating cycle is repeated. After a few such cycles the cathode 3 reaches its operating temperature which is maintained at the desired level by the thermal emission characteristics of the cathode 7.

Another form of the invention is shown in Figure 2 in which the emission of a cathode 15 within a tube 16 is regulated by a diode control tube 17 and a relay switch 18. This form of the device functions in a manner similar to the form shown in Figure 1 but in addition is provided with means to automatically cut off the power supply in case of failure of the control tube or the control circuit. Thus the cathode 15 will not become damaged by an uncontrolled flow of power.

The power to energize the cathodes and the control elements may be obtained in any suitable manner. As shown such power is obtained from a transformer 19 whose primary is connected to a suitable power source. A secondary winding 20 is connected to the cathode 21 in the tube 17 and the heater 22 for the controlled cathode 15. Desirably in this form of the invention the cathode 21 and heater 22 are connected in series.

The plate 23 of tube 17 is supplied with power from a secondary winding on the transformer 19. Connected in series with the plate 23 is the winding 24 of the relay 18 and the winding 25 of a protector relay 26. The relay 24 is adjusted to normally maintain its contacts 27, in the line leading to the cathode 21 and heater 22 closed, in the same manner as the control relay in the other form of the invention. The contacts 28 of the relay 26 are connected in the line leading to the heater 22 and are held closed while the relay 26 is energized.

Desirably a variable resistance or reactance 29 may be connected in parallel with the cathode 21 to provide for adjustment which may be necessary to properly maintain correct operating conditions at the cathode 21 and heater 22 and to provide flexibility in the apparatus to adapt it to control emission in different tubes or other electronic devices.

The winding 25 of the relay 26 contains more ampere turns than that of the winding 24 on the relay 18. The relay 26 therefore responds to smaller current flow than relay 18. When power is turned on to energize the apparatus the cathode 21 heats up and flow of current begins to build up within the tube 17. The relatively small current which first appears actuates the relay 26 first to turn on the power to the heater 22. Subsequently the relay 18 will act to cut off power to both the cathode 21 and heater 22. The cathode 21 will start to cool down until the winding 24 permits the switch contacts 27 to again turn on the power. A continuous series of cycles is thus maintained as in the device of Figure 1.

In the latter form of the invention there are additional events which take place involving additional elements as follows. The relay 26 is provided with an additional contact 30 to which is connected a shunting resistance 31 which in turn is connected to opposite sides of the line leading to the heater 22.

When the apparatus has been cut out of service the movable contact of the relay 26 rests upon the contact 30. Thus when the power is turned on no current flows to the heater 22. A circuit does however exist through the cathode 21, the resistor 31 and winding 20. The current flowing in this circuit starts to heat the cathode 21 which causes current to flow in the plate circuit of the

tube 17. The initial relatively small current which flows in the plate circuit actuates the relatively sensitive relay 26 to close the circuit to the heater 22.

As the cathode 21 becomes more electron emissive the on off cycle of the relay 18 is started. However, the circuit is so designed that the cathode 21 remains sufficiently emissive during the cool portion of its cycle to energize the winding 10 25 and thus keep the switch contacts 28 continuously closed.

If the tube 17 should fail or any portion of the relay control circuit should fail the switch contacts would open and the winding 25 would become completely deenergized at which time the contact 28 would open thus cutting off power to the heater 22 within the regulated tube 16. The tube 16 and its associated apparatus is thus protected from possible damage or malfunction.

Any suitable means may be employed to maintain the contacts 28 on the relay 26 closed during at least one on off cycle of the relay 18. An other means for accomplishing this is shown diagrammatically in Figure 3 wherein the heater 22 associated with the cathode 15 is supplied with power during normal operation of the apparatus but is disconnected from the power source when the control tube or any part of the control circuit fails.

In this form of the invention a cut-out relay 33 is provided having a winding 34 and switch contacts which make and break connection with the heater 22. The movable member 35 of the contacts is urged to break connection to the heater by a spring 36 or other suitable means. Such movement is resisted by a device operable to slow down its motion such as the dash pot 37 diagrammatically illustrated. The dash pot may be hydraulic or pneumatic in operation.

The dash pot 37 may be constructed to permit the member 35 to move readily into contacting position. Therefore when the apparatus is started and the winding 34 is energized the contactor 35 will close the circuit to the heater 22. The contacts are so adjusted that it requires a substantial movement of the member 35 to open the circuit. In operation therefore the on off cycles of the control relay will not open the circuit to the heater 22 because successive attempts 50 of the spring 36 to open the circuit will be cancelled by the resistance of the dash pot. A continuously closed circuit to the heater 22 will exist therefore until the control tube or circuit fails.

What I claim is:

1. Apparatus for regulating cathode emission comprising a cathode to be regulated situated within an electronic device, a control tube having at least a plate and cathode, power supply means connected to energize both cathodes, the emission of the cathode in said control tube being more critically dependent upon its temperature and faster in thermal response than the regulated cathode, power supply means having a connection to the control tube plate and a normally closed relay switch in said plate connection having its switch contacts connected to turn the power to said cathodes on and off, whereby the controlled cathode receives successive charges of current metered by the thermal emission characteristic of the cathode in the control tube.

2. Apparatus for regulating cathode emission comprising a cathode to be regulated situated within an electronic device, a control tube having at least a cathode and a plate, said latter cathode being more critically dependent on tempera-

ture and having a faster thermal response than the regulated cathode, a source of power, conductors connecting said power source to both cathodes, a source of power for said control tube plate, circuit connections from said latter power source to said plate, a relay switch having an electromagnet connected to be energized by said plate circuit and switch contacts connected to turn on and off the power to said cathodes and means to close said switch when the said electromagnet is deenergized whereby the regulated cathode receives successive charges of current metered by the thermal emission characteristics of the control tube cathode.

3. Apparatus for regulating cathode emission comprising a cathode to be regulated, situated within an electronic device, a control tube having at least a plate and cathode, power supply means for energizing both cathodes and the plate, a control relay switch and a cut-out relay switch connected to receive actuating current from said control tube, said cut-out relay being constructed to respond to a substantially smaller current flow than said control relay, the switching means on said cut-out relay being operable while the relay is energized to conduct current to the regulated cathode and when deenergized to cut off such current, the switching means on the control relay acting to turn on and off the power to the cathodes as the control tube becomes respectively partially conducting and conducting, the electrical and thermal characteristics of the control system being such that the control tube will be continuously at least partially conducting to maintain the cut off relay energized, whereby the regulated cathode receives current metered by the thermal emission characteristics of the control

tube cathode and will have its power cut off if the control tube or circuit fails.

4. Apparatus for regulating cathode emission comprising a cathode to be regulated situated 5 within an electronic device, a control tube having at least a plate and a cathode the latter cathode having a faster thermal emission response than the regulated cathode, power supply means for energizing both cathodes and said plate, a control relay switch and a cut-out relay switch connected to receive actuating current from said control tube, said cut out switch having contact members operating when the switch is energized to close the power supply line to said regulated cathode, delaying means connected to said contact members acting when the switch is deenergized to maintain closed said contacts for a substantial period of time after it is deenergized, contact elements on said control relay acting to 10 turn on and off the power to both cathodes respectively as the control tube becomes non-conductive and conductive at a rate faster than the cycle of operation of said delaying means whereby the regulated cathode is fed successive charges of current metered by the thermal emissive characteristics of the control tube cathode and will have its power cut off if the control tube or circuit fails.
